UNITED STATES PATENT OFFICE.

ARTHUR STEDMAN, OF CINCINNATI, OHIO.

BEDSTEAD.

SPECIFICATION forming part of Letters Patent No. 726,108, dated April 21, 1903.

Application filed March 24, 1902. Serial No. 99,771. (No model.)

To all whom it may concern:

Be it known that I, ARTHUR STEDMAN, a citizen of the United States of America, and a resident of Cincinnati, in the county of Hamilton and State of Ohio, have invented certain new and useful Improvements in Bedsteads, of which the following is a specification.

This invention relates to certain improvements in bedsteads, and more particularly in 10 children's bedsteads or cribs; and the object of the invention is to provide a bedstead or crib of a simple and inexpensive nature and of a strong and durable construction having improved means for permitting the folding of 15 the sides of the device.

The invention consists in certain novel features of the construction, combination, and arrangement of the several parts of the improved crib or bedstead whereby certain important advantages are attained and the 20 device is made simpler, cheaper, and otherwise better adapted and more convenient for use, all as will be hereinafter fully set forth.

The novel features of the invention will be 25 carefully defined in the claims.

In the accompanying drawings, which serve to illustrate my invention, Figure 1 is a side elevation showing a child's bedstead or crib constructed according to my invention, and 30 Fig. 2 is a similar view showing the device as it appears when collapsed or folded up for storage or shipment. Fig. 3 is an enlarged sectional view taken transversely through the improved crib or bedstead and showing the 35 same arranged close beside the side rail of an ordinary bedstead. In this view the lower ends of the legs are omitted. Fig. 4 is a sectional view similar to Fig. 3, but showing the several parts of the child's bedstead or crib 40 in folded or collapsed position. Fig. 5 is an enlarged partial perspective view showing the means for hinging the raised sides of the improved bedstead or crib. Fig. 6 is an enlarged partial section taken through the hinging 45 means for the side of the bedstead or crib in the plane indicated by the line *a a* in Fig. 3. Fig. 7 is a view somewhat similar to Fig. 5, but showing a modified form of the improved hinging means to be hereinafter referred to.

Referring first to Figs. 1 to 6, 11 indicate

the side rails of the bed-frame, and 22 indicate the end rails thereof, these side and end rails being preferably connected together at the corners of the bed-frame by means of 55 bolts or screws 33, passed through the parts at the joints between them. The bed-frame will also, by preference, carry a sheet of woven-wire fabric in a well-known way for supporting the bedding.

The improved bedstead or crib is formed with movable end frames, each formed of posts 44 and cross-bars 55, extended between said posts, near the upper ends thereof, the lower ends of the posts 44 being formed into 60 legs or supports, which may be provided with casters and which serve to support the bed-frame at a proper height above the floor. The upper ends of the posts 44 are extended above the bed-frame, as shown in Figs. 1 and 70 3, and the bars 55 between said posts form a railing extended across the head and foot ends of the bedstead or crib.

The end frames constructed as above described are adapted when the bedstead or 75 crib is in collapsed position, as shown in Figs. 2 and 4, to be folded beneath the bed-frame formed of the rails 1 and 2, and said end frames are held to the bed-frame by braces or links 6 and 7, as shown in dotted lines in 80 the figures, the links or braces 6 being adapted to be extended in horizontal position beneath the end rails 22 of the bed-frame when the end frames are in vertical position, and the braces or links 7 being adapted to 85 extend in diagonal or downwardly-inclined positions, as clearly shown in Fig. 1, when said end frames are in vertical position.

The improved bedstead or crib is constructed with raised side frames extended between 90 the end frames above and along the sides of the bed-frame, said side frames being held in hinged relation to the bed-frame and serving when raised to form, in connection with the raised end frames at the ends of the bedstead, 95 a raised railing extended entirely around the improved bedstead or crib and adapted to prevent the child therein from falling out of the bed. When the hinged side frames are lowered, they afford easy access to the bedstead or crib from the sides thereof and permit the device to be drawn up alongside of an 100

ordinary bedstead, so that care may be conveniently paid to the child during the night by a person lying in bed.

The side frames are formed of upper and lower bars or rails 20 and 14, connected together by upright parts 21, to produce a structure of sufficient strength, and each side frame so formed is connected to the bed-frame by means of hinging devices at its opposite ends, 10 the preferred form of such hinging devices being shown in detail in Figs. 5 and 6. As shown in these views, the hinging device at each end of each side frame comprises a lower member or part 8, formed of a piece or strip 15 of metal extended vertically up from the bed-frame, its lower end 9 being bent over at a right angle and perforated for the passage of the screw or bolt 3, so that the hinging device is held to the bed-frame by the same 20 means which holds the rails of said frame together at the corners thereof. The upper end 10 of the strip or piece 8 of metal is bent or curved outwardly or toward the outer edge of the bed-frame and carries a pivot-pin or 25 rivet 11, on which is held the upper or swinging hinge member 12, a washer 15 being interposed between these two parts at the pivot-point to give sufficient clearance and permit 30 the two members of the hinge to work easily upon each other.

The upper or swinging member 12 of the hinge connection is extended transversely across the end of the lower rail or bar 14 of the hinged side frame of the improved bedstead or crib and is secured to said end of the rail by means of a screw 13, which is passed through an opening in the hinge member and takes into the center of the end of the rail, as shown clearly in Fig. 6. The extremity 16 35 of said hinge member 12 is bent at right angles to the body portion thereof and is extended along the inner surface of the rail 14, as clearly shown in the drawings, its extremity being secured to said rail by means of a 40 screw 17 in such a way as to serve as a brace to hold the hinge member 12 securely and rigidly upon the end of the rail.

Where the hinge member 8 is made of enough height to hold the lower rail or bar 50 14 of the hinged side frame at a considerable distance above the bed-frame, I prefer to interpose between the bed-frame and said rail 14 another rail or bar 18, extended longitudinally along the side of the bed-frame and held at its ends by means of screws 19, passed through perforations in the central portions of the members 8. These rails or bars 18 along the sides of the bed-frame serve to hold the bedding against displacement when the 55 60 hinge-pivots of the swinging or folding side frames are at some height above the bed-frame. Where the hinge-pivots of the side frames are nearer the bed-frame, the hinge members 8 being shorter, as shown in Fig. 7, 65 the bars or rails 18 are dispensed with as being unnecessary.

The upper rails or bars 20 of the swinging

side frames of the improved bedstead or crib are made of greater length than the lower rails 14 thereof, as shown in Figs. 1 and 2, and 70 the extremities of said upper rails or bars 20 are adapted when the side frames are in raised position to take snugly against the inner sides of the posts 4 4 of the end frames, being provided with eyes adapted to be engaged by 75 hooks 22, carried on said posts 4 4, in such a way as to securely fasten the side frames in their raised position and also to prevent the end frames from being lowered, so that the bed cannot when said hooks 22 are engaged 80 with the eyes be accidentally collapsed.

When it is desired to fold up or collapse the improved bedstead or crib, the hooks 22 are disengaged from the eyes of the side frames, so as to permit the end frames to be 85 folded down beneath the under side of the bed-frame, as shown in Fig. 2, whereupon the hinged side frames are folded over inwardly upon the bed-frame, as shown in Fig. 4. In this way it will be seen that the improved 90 bedstead or crib may be very compactly folded up, so as to occupy but very little space, so that it is much better adapted for storage or shipment.

When the improved bedstead or crib is in 95 use, the swinging side frames being raised will by reason of the peculiar construction of the hinge connections with laterally-bent portions 10 and 12 on their members stand in alinement with the posts 4 4 at opposite 100 ends thereof, so that the sides of the crib or bedstead will present a smooth and even surface between the end posts 4 4 from top to bottom, and the hooks 22 on the posts 4 serve by engagement with the swinging side frames 105 to insure a very rigid and strong structure and effectually prevent accidental collapse or folding of the bed, and when it is desired to lower one or both of the swinging side frames—as, for example, to permit the improved crib to 110 be pushed close up to the ordinary bedstead, so that attention may be more conveniently given to the child in the crib at night—the hooks 22 may be disengaged from the eyes of the swinging side frame, and said frame may 115 be swung outwardly into lowered position, as shown at the right in Fig. 3. The upper ends of the members 8 of the hinge connections for the side frames being bent outwardly and the said side frames being held eccentrically 120 with relation to the hinge-pivots 11 of the hinge connections, it will be seen that when the side frames are thus swung into lowered 125 positions they will be flush against the outer sides of the bed-frame, so that the improved crib may be pushed up closely adjacent to the side rail x of the ordinary bedstead without leaving a space between the two and without danger of breaking or straining the hinges or the side frames in any way.

When the longer lower hinge members 8 (shown in Figs. 1 to 5) are employed, the rail or connection 18, extended between the said members below the laterally bent or curved

upper portions 10 of said members, will also be extended in line with the side frames when the latter are raised, so that there will be no unevenness or irregularity in the sides of the bedstead or crib from top to bottom thereof.

From the above description it will be seen that the improved child's bed or crib constructed according to my invention is of an extremely simple and inexpensive nature and is especially well adapted for use, since it is light and strong and permits of being compactly folded up or collapsed when not required for use. Also by reason of the peculiar hinge connections by means of which the side frames are held to the bed-frame the crib may be drawn up much closer to the ordinary bedstead than is possible where other forms of hinge are employed, and the danger of breaking of the side frames or hinges is altogether avoided.

It will also be obvious from the above description that the improved child's bed or crib is capable of some modification without material departure from the principles and spirit of the invention, and for this reason I do not wish to be understood as limiting myself to the precise form and arrangement of the several parts of the device as herein set forth.

Having thus described my invention, what I claim, and desire to secure by Letters Patent, is—

1. The combination of a bed-frame having side rails and provided with end posts in line with said side rails, side frames extended above the side rails between the end posts and adapted to be raised and lowered and arranged, when in raised positions, in line with the said end posts between which they extend, upper hinge members carried on the side frames and having portions extended away from said side frames toward the edges of the side rails, and lower hinge members held on the bed-frame and having pivotal connection with the extended portions of the upper hinge members at points outside of the side frames, substantially as set forth.

2. The combination of a bed-frame, having side rails and end posts in line with said side rails, lower hinge members connected with the bed-frame in line with the end posts and extended up above the same and having their upper ends extended outwardly toward the lateral edges of the bed-frame, parts held at

their ends to the lower portions of the said lower hinge members and extended along the sides of the bed-frame in line with said end posts, side frames and upper hinge members carried upon the side frames and having portions extended away from said side frames and adapted, when said side frames are in vertical position, to be extended outwardly beyond the outer sides thereof, the side frames when in vertical positions being alined with said end posts and said outwardly-extended portions of the upper hinge members having pivotal connection with the outwardly-extended upper ends of the lower hinge members to hold the side frames for pivotal movement upon the bed-frame, substantially as set forth.

3. The combination of a bed-frame, lower hinge members connected with and extended above the bed-frame, upper hinge members pivotally connected with the upper ends of the lower members and swinging side frames having at the lower parts bars or rails across the ends of which the upper hinge members are transversely extended, the side frames being held to said upper members eccentrically with relation to the pivot connections between the hinge members, substantially as set forth.

4. The combination of a bed-frame, lower hinge members connected with and extended above the bed-frame and having their upper ends bent outward toward the lateral edges of the bed-frame, upper hinge members pivotally connected with the upper ends of the lower members, washers interposed between the hinge members at their pivot connections and swinging side frames having at their lower parts bars or rails across the ends of which the upper hinge members are transversely extended, the side frames being held to said upper members eccentrically with relation to the pivot connections between the hinge members and the upper members having their extremities bent at right angles and extended along and secured to the inner sides of said lower bars or rails of the side frames, substantially as set forth.

Signed at Cincinnati, Ohio, this 20th day of March, 1902.

ARTHUR STEDMAN.
